UNITED STATES PATENT OFFICE.

BURT D. STEVENS, OF RIVERSIDE, ILLINOIS, ASSIGNOR TO THE MIEHLE PRINTING PRESS & MANUFACTURING COMPANY, OF CHICAGO, ILLINOIS, A CORPORATION OF ILLINOIS.

JOGGER FOR PRINTING-PRESSES.

1,107,859.

Specification of Letters Patent. Patented Aug. 18, 1914.

Application filed November 1, 1911. Serial No. 657,975.

To all whom it may concern:

Be it known that I, BURT D. STEVENS, a citizen of the United States, residing at Riverside, in the county of Cook and State 5 of Illinois, have invented certain new and useful Improvements in Joggers for Printing-Presses, of which the following is a specification.

My invention relates to printing press 10 mechanism, and refers particularly to joggers used in connection therewith.

It has heretofore been customary, when 15 a printed sheet of paper passes from the delivery mechanism to the receiving table, to bring laterally reciprocating jogger members in contact with the edges of the sheet, whereby the latter is moved to a predetermined position and the sheets of paper are brought to a more or less even position 20 in a pile. The disadvantage with this mechanism has been that the paper, particularly if it is thin, is very apt to become crumpled when being moved by the jogger members. A further disadvantage lies in the fact that 25 when one printed sheet is moved over another, the ink, which has not had an opportunity to become thoroughly dried, is very apt to smear.

It is the object of my invention to place 30 the sheets of paper in an even pile, and at the same time to do away with the tendency to crumple the paper and smear the ink. I accomplish this result by employing currents of air which gently and easily force 35 successive sheets of paper against the guide members located on two sides of the receiving table. The above-mentioned disadvantages of the old system of operation are not only avoided in this manner, but the 40 currents of air serve to promote the rapid drying of the ink on the printed sheets. The currents of air preferably come from two sides of the receiving table, and may be continuous or intermittent. The jets 45 through which the air passes may also be stationary or vertically reciprocating according to the requirements of various classes of work, and the apertures may be of any suitable cross section, the term slots 50 herein being used in a general sense and not as defining openings of any particular shape. These and other advantages of my invention will be more readily understood by reference to the accompanying drawings, which

represent preferred embodiments of my improvements, and in which—

Figure 1 is a plan of a portion of a printing press, showing the receiving table and jogger mechanism in position; Fig. 2 is a side elevation of the parts shown in Fig. 1; and, Fig. 3 is a vertical longitudinal section through the same general type of printing press and receiving table shown in Fig. 1, but illustrating the air jets as being vertically reciprocating.

The receiving table 10 is of the well known type, and is provided with the side guide members 11 and 12, which are adjusted in desired positions by means of the brackets 13 having the bolts 14, which operate in the slots 15. These members 11 and 12 have the apertures 11^a and 12^a to allow the escape of air, in the manner which will later be more fully explained. Placed near two edges of the receiving table 10 are the side members 16 and 17, which may be either stationary or adjustable. The pipe 18 is located on two sides of the receiving table 10, and occupies a position parallel to the side members 16 and 17. In each of the latter are the vertical slots 19, each of which is covered on its exterior by a cap 20, which communicates through a pipe 21 with the pipe 18. Each of the caps 20 is of such shape that it supplies air to the entire length 75 of the corresponding slot 19.

Carried on the brackets 22 of the printing press is the shaft 23, on which are mounted pulleys 24, over which pass the delivery tapes 25. Also carried by the brackets 22 is 90 the transverse fly shaft 26, to which the fly rods 27 are rigidly attached. When the printing press is operated the fly shaft 26 rotates in the well known manner, and delivers successive sheets of paper to the receiving table 10.

The operation of my invention may now be readily understood: The paper which comes from the printing portion of the printing press is delivered to the fly rods 27 by means of the delivery tapes 25. The fly shaft 26 is then rotated by suitable well known mechanism, and delivers the paper to a position directly above the receiving table 10. Currents of air are meanwhile 100 coming from the various slots 19 in the side members 16 and 17, so that the sheet descends on these currents of air and is bodily 105

carried into position so that two edges of the sheet are brought into contact with the guide members 11 and 12, through the apertures 11^a and 12^a of which the air escapes. 5 This same operation is repeated as successive sheets of printed paper are delivered from the fly, so that the even pile 28 is gradually formed. The air coming through the slots 19 may flow continuously during 10 the operation of the press, or by suitable mechanism its flow may be intermittent and started only as the sheet of paper is delivered from the fly.

In Fig. 3 I have shown a slight modification of my invention. Attached to the fly shaft 26 is a crank 29, which is pivotally connected to the link 30, which, in turn, is connected to the rod 31. Carried by the rod 31 is the bracket 32, which supports the 20 air pipe 18 having air nozzles 33. It will be evident that when the fly shaft 26 is rotated to deliver paper to the receiving table 10 the link 30 is raised by the action of the cam 29, and, correspondingly, the bracket 32 is elevated. This causes the pipe 18 to move upwardly, carrying the nozzles 33 up in the slots 34, so that as the paper is delivered 25 the nozzles 33 are in their highest positions. As the fly moves back into its normal position, shown in the drawings, the nozzles 33 are lowered, and the paper is thereby gradually allowed to descend as the nozzles are lowered, at the same time the action of the air serving to carry the sheet against the 30 guide members 11 and 12. If the nozzles 33 are directly connected with the pipe 18, as shown in Fig. 3, the entire pipe 18 is reciprocated in a vertical plane, whereas if the nozzles 33 are connected to the pipe by 35 means of flexible rubber couplings or the like, the nozzles alone may be reciprocated, and the pipe 18 may remain in a stationary 40 position.

It will be apparent to those skilled in the 45 art that many changes could be made in the detailed construction of the parts which I have described without departing from the spirit or scope of my invention. For example, instead of using a fly, any other suitable paper delivering means could readily 50 be employed.

What I claim is:

1. In a printing press, the combination of delivery means, a receiving table having a 55 pair of adjustable guide members substantially at right-angles to each other, and a pair of side members parallel to said guide members, each of said side members having a delivery slot therein, and means for delivering air through said slots, whereby the sheets of paper successively coming from 60 said delivery means will be directed into contact with said guide members, substantially as described.

65 2. In a printing press, the combination of

delivery means, paper receiving means, a guide member on said receiving means, means for directing an air jet toward said guide member, and means for vertically reciprocating said jet directing means as said 70 delivery means is operated, whereby the sheets of paper coming successively from said delivery means will be brought into contact with said guide member, substantially as described. 75

3. In a printing press, the combination of delivery means, a receiving table, a pair of guide members on said receiving table mounted substantially at right-angles with each other, means for directing an air jet 80 toward each of said guide members, and means for vertically reciprocating said jet directing means as said delivery means is operated, whereby the sheets of paper coming successively from said delivery means 85 will be directed into contact with said guide members, substantially as described.

4. In a printing press, the combination of delivery means, a receiving table having a guide member thereon, a side member parallel to said guide member, said side member having a delivery slot therein, and means for delivering air through said slot in a substantially horizontal direction toward the 90 guide member and transverse to the direction of travel of the sheet, whereby the sheets of paper successively coming from said delivery means will be directed laterally into contact with said guide member, substantially as described. 95

5. In a printing press, the combination of delivery means, a receiving table having thereon an apertured guide member, a side member arranged substantially parallel to the guide member and to the direction of 105 travel of the delivered sheets and having therein delivery slots directed toward the apertured guide member and transverse to the direction of travel of the sheets, and means for delivering air currents through 110 said slots toward and through the apertures of the guide member, whereby to carry the sheets of paper laterally into contact with the guide member, substantially as described. 115

6. In a printing press, the combination of delivery means, a receiving table having thereon a pair of apertured guide members arranged at substantially right angles to each other, a pair of side members arranged substantially parallel to the guide members and having therein delivery slots directed toward the apertured guide members, and means for delivering air currents through 120 said slots toward and through the apertures of the guide members, whereby to carry the sheets of paper into contact with the guide members, substantially as described. 125

7. In a printing press, the combination of delivery means, a receiving table having 130

thereon a pair of guide members provided with vertically elongated apertures and arranged at substantially right angles to each other, a pair of side members arranged substantially parallel to the guide members and having therein vertically elongated delivery slots directed toward the apertured guide members, and means for delivering air currents through said slots toward and through

the apertures in the guide members, whereby to carry the sheets of paper into contact with the guide members, substantially as described.
